By Jesse R. Stone

His Attorney

UNITED STATES PATENT OFFICE.

LOUIS T. MATHEWS, OF HOUSTON, TEXAS, ASSIGNOR, BY DIRECT AND MESNE ASSIGNMENTS, TO THE LET-TA POIN-TA MANUFACTURING COMPANY, OF HOUSTON, TEXAS, A CORPORATION OF DELAWARE.

POSITION INDICATOR FOR TYPING MACHINES.

Application filed March 30, 1925, Serial No. 19,240. Renewed October 17, 1927.

My invention relates to an attachment for copyholders for use on typewriters, type-setting machines and the like.

There are various copy holding devices 5 now in use for holding the copy which is to be reproduced. The notes to be copied are usually typewritten material, although it is occasionally a matter of printed articles from newspapers and the like which is to be re-typed. The devices now in use employ a fixed horizontal marker relative to which the copy is gradually raised to disclose one line after another of the printed matter which is to be copied.

15 An object of the invention is to provide a laterally moving pointer, adjustable to move in unison with the typing of the copy, so as to continually indicate the exact letter or other character which is being typed.

20 Another object is to provide an indicator to mark the character being typed which will be actuated automatically by the manipulation of the keys of the typing machine. It is also desired to provide means of adjustment 25 of the operating mechanism which will adopt the device for use with different sizes of printed copy matter.

Referring to the drawing herewith, Fig. 1 is a front elevational view of a device employing my invention. Fig. 2 is a broken detail in front elevation, showing a slightly different embodiment of the marker; Fig. 3 is a transverse sectional view of the reel employed with my marker, and Fig. 4 is a 35 side view of the adjusting spools which may be employed. Like numerals of reference are employed to designate like parts in all the views.

In the drawing, I have shown my attachment as applied to a typewriter indicated as 40 1, having on the rearward side thereof an upright copy holder 2. While I have indicated the device as applied to a typewriter, it is to be understood that the same may be 45 employed upon linotypes and other similar type-setting machines, as well as upon any ordinary make of typewriter.

The typewriter in the drawing is somewhat diagrammatically shown, there being a 50 keyboard 3 and a carriage 4 which is moved to the left, as seen in Fig. 1, by the manipu-

lation of the keyboard, as is well understood in the operation of typewriters.

The copy holder shown in the drawing comprises an upright plate or board 5 which furnishes a back or support for the copy which is to be reproduced by the typewriter. The sheet of copy is held in position upon the plate by means of a spring pressed rod 6. The line which is being copied is marked by means of a straight edge or rule 7 mounted upon a supporting bracket or stand 8. This rule is stationary and the stand or back plate is moved vertically relative to the marking rule by means of mechanism not shown, but which is well understood in the art, and comprises no part of my invention.

The invention consists in the employment of a pointer movable along the straight edge which marks the line being copied to indicate the exact letter which is being typed at any time. This will make it unnecessary for the typist to watch his printed matter, and it will only be necessary for the typist to watch the progress of the pointer along the 75 copy.

In the drawing the pointer is indicated at 9. It comprises an upwardly extending point attached to a supporting tape or cord 10 which is adapted to be reeled up onto a 80 spool within the housing 11. In Fig. 3 the interior of the housing 11 is shown. There is a central roller 12 mounted upon a central shaft 13 and having a spring 14 to hold the tape in retracted position. This type of 85 spring operated spool or reel is well known. The tape or cord 10 is secured at 15 to the surface of the roller 12 and will be wound up on the spool by the operation of the spring.

The housing 11 for the reel is mounted upon a bracket 16 secured to the frame 17 of the straight edge. The bracket is forked at its outer end to form a bearing to receive the shaft 13. The bracket may be adjustably 95 clamped to the frame 17 by any desired means.

The end of the cord or tape 10 adjacent the pointer is secured to a cord 18 which serves to move the tape 10 and the marker through 100 the operation of the type machine. This is performed by extending the cord 18 over a

roller or pulley 19 mounted upon a bracket 20 so as to hold the line 10 parallel with the straight edge. The bracket 20 is secured at its upper end 21 to the rod 17 of the frame, and is extended downwardly below the pulley 19 and supports thereon a reel 22 mounted rotatably upon a shaft 23 secured in the bracket. As shown in Fig. 4, the bracket 20 may be formed of a strap of iron or other metal extending downwardly forming a loop at its lower end and recurved to be again secured to the upper arm of the bracket at the pivotal point of the pulley 19. The reel shaft 23 is thus supported at both ends for greater strength. Referring also to Fig. 4 it will be noted that the reel has a series of drums 24 of different diameters thereon, so that the rate of movement of the pointer along the straight edge may be adjusted for different sized type. The line 18 is secured about an intermediate drum and will be reeled up thereon as the reel is rotated.

The reel is adapted to be rotated by a cord or line 26 secured at 27 to the largest of the drums upon the reel, and wound thereon for a few turns and then extended laterally across the top of the typewriter and secured at 28 to the arm 29 mounted upon the end of the carriage 4. Thus when the carriage is moved laterally toward the left in the drawing, the cord 26 will rotate the drum 22 and reel up the cord 18 upon the selected drum to move the pointer 9 at the rate desired. Thus the pointer will be moved from the left to the right following the copy so that the pointer will indicate at each moment the letter or character which is being copied. It will be obvious that the amount of movement at each imprint made by the type machine may be adjusted so that the pointer will accurately indicate at all times the point at which the operator is copying. The tension of the spring 14 within the housing will tend to draw the pointer resiliently back toward the housing, and for this reason, if any character is retyped for any reason, the marker will move backwardly so as to remain always at a point indicating the character being typed.

The spring within the housing exerts a constant tension upon the pointer, but it is to be understood that this tension may be exerted equally well by means of a weight such as is disclosed in Fig. 2. In this modification, the tape or cord 10' is passed over a roller 30 mounted in a bracket 31 upon the frame, and a weight 32 is secured on the line below the pulley 30. The weight will thus exert a constant tension on the line 10' to move the pointer in the same manner as in the previous embodiment.

The operation of this device has already been set forth. The operation of the keyboard of the typewriter will move the carriage 4 in the usual manner so as to operate

the pointer along the edge of the marker 7. This will be a great convenience to the operator in that it will be practically impossible to omit a word or letter without its being shown at once by the pointer.

When the typist has occasion to stop a moment for consulting a reference or for other reasons, the point at which the copy was stopped will be indicated at once so that no time need be lost in finding the place. By use of drums of different sizes upon the reel 22, the progress of the pointer along the edge of the marker may be adjusted to adapt it for use in copying ordinary printed matter, or for previously typewritten matter so that the device may be employed in the copying of any type of printed characters. The further objects and advantages of the invention will be apparent to those skilled in the art.

What I claim as new and desire to protect by Letters Patent is:

1. In a device of the character described, including a typewriter, a copy holder adjacent thereto, and a line marker relative to which the copy holder is movable, the combination of a bracket positioned at one side of said copyholder, a series of drums of different diameters mounted rotatably on said bracket, a reel at the opposite side of said copyholder, a tape on said reel connected at one end to one of said drums, a pointer on said tape, and a line connected with the carriage of said typewriter and passing over one of said drums, and adapted to move said tape in the manner described.

2. In a device of the character described, a typewriter having a carriage thereon, a frame adjacent said typewriter, a copyholder adjustable vertically on said frame, a stationary line marker on said frame and adapted to bear against the front of said holder, a flexible line, means to hold said line resiliently against said copyholder, a pointer on said line, a reel to which said line is connected, a series of drums of various diameters on said reel, and a cord connected with said carriage and one of said drums.

3. In a device of the character described, the combination with a typewriter having a moving carriage thereon, a frame adjacent said typewriter, a copyholder movable up and down on said frame, and a line marker on said frame at the forward side of said copyholder, of a bracket on said frame adjacent one end of said carriage, a reel with drums of different sizes on said bracket, a flexible line held resiliently at the side of said frame opposite said bracket and connected with said reel, a pointer on said line, and means connected with said carriage and said reel to move said line and said pointer at the desired rate of travel along said marker.

4. In a device of the character described,

the combination with a typewriter, a frame adjacent thereto, a copyholder movable on said frame, a stationary line marker on said frame, a flexible line held resiliently at one end of said marker, a pointer thereon, and means operated through the carriage of said typewriter to draw said marker across said

holder at various rates of movement, as desired.

In testimony whereof I hereunto affix my ¹⁰ signature this 26th day of March A. D. 1925.

LOUIS T. MATHEWS.
